UNITED STATES PATENT OFFICE.

EDWARD T. BURROWES, OF PORTLAND, MAINE.

AWNING OR CURTAIN FOR OPEN CARS.

SPECIFICATION forming part of Letters Patent No. 516,762, dated March 20, 1894.

Application filed May 26, 1893. Serial No. 475,620. (No model.)

To all whom it may concern:

Be it known that I, EDWARD T. BURROWES, a citizen of the United States, residing at Portland, in the county of Cumberland and State 5 of Maine, have invented certain new and useful Improvements in Awnings or Curtains for Open Cars; and I do hereby declare the following to be a full, clear, and exact description of the invention, such as will enable others 10 skilled in the art to which it appertains to make and use the same.

This invention is especially adapted for street and other railway cars commonly termed "open cars," such cars being constructed with 15 out sides and provided with posts for supporting the roof, and located at either end of the seats which extend cross wise of a car. Curtains are required for protection of passengers from the sun and rain upon such cars, 20 but owing to the strong wind to which such curtains would sometimes be subjected, the difficulty heretofore has been to devise a practical and inexpensive method for properly securing the curtains at their sides without seriously interfering with the ingress and egress 25 of passengers.

The object of my invention is to produce the result desired in a curtain for cars of the above description in as cheap and effective 30 a manner as possible.

To this end my invention consists in the various novel features and construction of the attachments to a spring actuated awning or curtain adapted to shut out sun and rain 35 from open railway cars, to be fully set forth in the following specification and claims and clearly illustrated in the accompanying drawings forming a part thereof, of which—

Figure 1. represents a broken elevation of 40 a portion of an open street car, having my improvements attached. Fig. 2. is a sectional plan of one of the posts supporting the roof of a car, and provided with grooves in which are shown the edges of two of my improved 45 awnings. Fig. 3. shows those parts illustrated in Fig. 2, in modified form. Fig. 4. is a cross-section of the lower edge of an awning or curtain inclosing a curtain stick to be hereinafter explained, and one of my improved pendants 50 for operating the curtain at either side or the bottom; the latter being shown in elevation. Fig. 5. is a broken elevation of a portion of a

curtain or awning, with its stiffening bar or "stick" at its bottom and the pendants.

Like reference letters denotes corresponding parts throughout the various views.

A, is the floor of an open street car.

B, are seat supports, C, being the reversible backs, and D, are the posts supporting the roof E.

My improved awnings or curtains F, are mounted at their top upon spring actuated rollers G, which differ from the ordinary spring curtain roller only in the matter of the spring which requires to be considerably 65 stiffer or stronger.

At the bottom of the awning or curtain F, is attached a curtain stick H, which is formed hollow and contains spring actuated holding mechanism such as described in United States 70 Letters Patent to Hall, No. 453,409, dated June 2, 1891, and No. 483,490, dated September 7, 1892, and also patents issued to myself, No. 476,783, dated June 14, 1892, and No. 493,885, dated March 21, 1893; the extension tip h, of 75 these curtain sticks H, moving in grooves d, provided in the posts D, as seen in Fig. 3.

It may be here mentioned that the various views in the drawings are not made on the same scale;—Figs. 2 and 3, for instance are 80 on a much larger scale than in Fig. 1, and the parts shown in Figs. 4 and 5 are yet larger than Figs. 2 and 3.

The awnings or curtains F, are made double or in two thicknesses of material and between these at proper intervals are inserted 85 flexible steel strips I, which may be about one eighth of an inch thick and one half inch wide, edges rounded and galvanized to prevent unnecessary wear or discoloration of the cloth 90 of which the curtains are made.

The awnings or curtains F, are made wide enough to reach within the groove d, in order to exclude rain from the car, and if permitted to rub on either side of the groove when raised 95 or lowered they would wear too rapidly to be of practical value: To prevent this I pass a copper rivet J, through both thicknesses of the curtain F, and the flexible steel strips I, at a point near each end of said strip, so that 100 the round heads of said rivets come in contact with the sides of said groove instead of the curtain material. The edges of the curtains or awnings F, would have also a tend-

ency to wear ragged very rapidly if allowed to scrape against the bottom of the grooves *d*, while being operated, and to obviate this difficulty I allow the ends of the flexible strips 5 *I*, to project slightly beyond the edge of a curtain, as seen best in Fig. 2, and take the wear in that direction instead of the curtain. The extension tips *h*, may be formed integral with or attached to the rods *h'*, shown in section Fig. 5, and the latter are operated by the pendants *K*. These pendants may be of the form shown in the patents previously mentioned herein, but as the awnings or curtains for open cars are as likely to be required 10 to be operated upon one side as upon the other, some such form of pendant as for instance the substantially heart shaped pendant shown in Fig. 4, will be found convenient, as the extensions *h*, are handy to grasp at either side 15 when the curtain is below the operator. The bars *I*, hold the awning or curtain *F*, at all times within the grooves *d*, and effectively prevent its collapsing.

When building a car with a view to the 20 use of my improved awnings or spring actuated curtains, the posts *D*, will have the grooves *d*, formed in their sides as seen in Fig. 2;—but in applying my curtains to old cars, cleats, *D'*, are secured to the posts *D*, 25 which form the grooves for the curtains.

The curtains may be made of thin material and double for their entire length, or they may be formed of thicker material, and nar-

row strips of the same be sewed across at proper intervals to form pockets for inclosing 35 the metal bars *I*, which in either construction are not in view from either side.

Having described my invention, what I claim is—

1. A spring actuated awning or curtain for 40 open cars, provided with pockets, a flexible piece of material within each pocket, the ends of which project slightly beyond the edges of the curtain, and a projection upon each side of the curtain near each end of each rod, 45 whereby the edges of the curtain are prevented from coming in contact with the posts of the car, and means for securing the curtain at any desired point, substantially as set forth.

2. A spring actuated awning or curtain for 50 open cars, provided with transverse pockets, a flexible piece of material in each pocket, the ends of which project slightly beyond the curtain, and a rivet through the two thicknesses of the curtain forming the pocket and 55 through the piece of material, near each end, whereby the edges of the curtain are prevented from coming in contact with the posts of the car, substantially as set forth.

In testimony whereof I affix my signature in 60 presence of two witnesses.

EDWARD T. BURROWES.
